US0D1068765S

(12) **United States Design Patent** (10) Patent No.: **US D1,068,765 S**
(45) Date of Patent: ** Apr. 1, 2025

(54) **HARD DISC**

(71) Applicant: **Jian Zhongrui Electronics Co., Ltd.**,
Ji'an (CN)

(72) Inventors: **Xiaodong Ma**, Shenzhen (CN); **Xude Zhou**, Ji'an (CN); **Jianghua Yang**, Ji'an (CN); **Xianzhang Wu**, Ji'an (CN)

(73) Assignee: **Jian Zhongrui Electronics Co., Ltd.**,
Ji'an (CN)

(**) Term: **15 Years**

(21) Appl. No.: **29/861,775**

(22) Filed: **Dec. 2, 2022**

(51) LOC (15) Cl. **14-02**

(52) U.S. Cl.

USPC **D14/348**; D14/435

(58) **Field of Classification Search**

(57) **CLAIM**

The ornamental design for a hard disc, as shown and described.

DESCRIPTION

FIG. 1 is a front perspective view of a hard disc, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the hard disc, which form no part of the claimed design.

1 Claim, 8 Drawing Sheets
